UNITED STATES PATENT OFFICE.

DORAS A. STILES, OF DURHAM, CONNECTICUT.

DESIGN FOR A TOY BANK.

Specification forming part of Design No. **6,156**, dated September 24, 1872.

To all whom it may concern:

Be it known that I, DORAS A. STILES, of Durham, in the county of Middlesex and State of Connecticut, have invented a new Design for Toy Bank; and I do hereby declare the following, when taken in connection with the accompanying drawing, to be a full, clear, and exact description of the same, and which said drawing constitutes part of this specification and represents a front view.

This invention relates to a modification of the design for toy bank for which Letters Patent were granted to me January 25, 1872; and it consists in the peculiar configuration of the roof, as more fully hereinafter described.

In the design before referred to the lines of the roof are concave from the cornice to the deck. In this design the lines of the roof are convex from the cornice to the deck, which constitutes the distinguishing characteristic of this design. Dormer-windows may be added, if desired.

I claim as my invention—

The design for toy bank, as herein described and shown in the accompanying illustrations, with or without dormer-windows.

DORAS A. STILES.
